E. BIGNELL,
PILE,
APPLICATION FILED JULY 13, 1914.

1,185,582.

Patented May 30, 1916.

UNITED STATES PATENT OFFICE.

EDWARD BIGNELL, OF LINCOLN, NEBRASKA.

PILE.

1,185,582.

Specification of Letters Patent.

Patented May 30, 1916.

Application filed July 13, 1914. Serial No. 850,789.

To all whom it may concern:

Be it known that I, EDWARD BIGNELL, a citizen of the United States, residing at Lincoln, in the county of Lancaster and State of Nebraska, have invented certain new and useful Improvements in Piles; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to subsurface structures, such as piles, sheet piling, or caissons, and more particularly to a structure comprising means for delivering jets of water in advance thereof to form an excavation, 20 into which the structure may sink, and along the sides of the structure to step displaced material upwardly along the sides thereof, and thereby not only lubricate the sides, but also remove the material displaced by the 25 excavating jet.

It is the object of the present invention to provide improved details of structure for supplying and delivering the excavating and stepping jets, the preferred forms of which 30 are illustrated in the accompanying drawings, wherein:—

Figure I is an elevation of a concrete pile containing my improvements. Fig. II is an enlarged central, longitudinal section of the 35 pile. Fig. III is a transverse section on the line III—III, Fig. II, but indicating the embedded tubes 33 in full lines. Fig. IV is an enlarged detail perspective of one of the side nozzle sockets. Fig. V is a detail 40 perspective of one of the preferred form of side nozzles. Fig. VI is a cross-section of a portion of the pile, on the line VI—VI, Fig. II, showing the hoist link.

Referring more in detail to the parts:—1
45 designates a concrete pile, having a central longitudinal channel 2, formed by molding the concrete over a form, preferably consisting of a middle section 4, of relatively thin sheet iron and end sections 5 of metal 50 tubing; the intermediate sheet metal section having its ends overlapping the metal tube in order to form a close joint. By providing a thin sheet metal core section a less expensive structure is provided and the core 55 is rendered practically as efficient as though

the tubing were extended entirely through the piling.

The upper tube section 5 extends beyond the upper end of the pile and carries a fitting 7, preferably of the construction hereinafter described, and connected with a laterally directed conduit 8 through which water for the side jets may be supplied. Projecting through the fitting 7 is a pipe 12, which extends into and through the interior 60 of the tube 5; the diameter of the pipe being sufficiently less than that of the tubing to provide an annular space 13 therebetween.

The lower tubing section 5 terminates at or within the lower end of the pile, and 65 mounted on the lower end of the fitting (preferably by screw threads) is a reduction fitting 16, having a head 17, for receiving the tubing section, and a tapered lower end 18 forming a nozzle, the end of which terminates flush with the bottom of the pile, and the channel 19 of which converges toward the outlet to restrict the flow and thereby increase the force of the jet.

The fitting 16 is preferably provided with 70 outstanding ribs 20 at various points throughout its length, to reinforce the head and anchor the same in the concrete.

The interior of the nozzle end 18 is tapered, and threaded onto the lower end 75 of the inside pipe 12 is a tapered plug 21, having an anchor groove 22 carrying a packing ring 23 for closely engaging the inner surface of the nozzle when the inside pipe is forced downwardly within the pile, so 80 that when the plug is seated in the nozzle, water delivered into the outer tubing, through conduit 8, is confined within the head of the fitting and does not mingle with water that is delivered through the inner 85 pipe 12 to the nozzle 18.

With this construction, it is possible to deliver separate volumes of water under different pressures to the excavating and stepping nozzles, and by providing the nozzle 100 with a restricted outlet, the force of the excavating jet is increased.

The sheet metal core 4 and tubing 5 are provided at intervals throughout their length with apertures 30 which register with 105 transverse channels 32 in the concrete pile, and fitting within said channels and apertures are tubes 33, which preferably terminate in sockets 34 in the sides of the pile.

Threaded onto the outer ends of the tubes 110

33 are nozzle tips 36, having upwardly directed and flared outer ends 37 lying close to the outer surface of the pile; the nozzles being preferably formed of street L's, or 5 the like, with the free ends curved to provide the flared or rectangular mouths 38, and enable them to lie flat against the surface thereof when the surface of the pile is convex (as shown in the present drawings).

10 In order to provide an effective sealed connection between the high and low pressure conduits 12, 4 and 5, and seat the high pressure pipe 12 in its nozzle, I thread a collar 40 onto the upper end of the inside pipe 12, 15 so that when the parts are in place the collar will seat in the fitting 7 above the line of flow from the supply pipe 8 to the large conduit in the pile, and thread a section of pipe 42 into the upper end of the collar 40, 20 so that the upper end of said section may project above the fitting 7 to carry the high pressure supply pipe 43. A gland 45 is slidably mounted on the connecting pipe section 42, and adapted to thread into the upper end 25 of the fitting 7, so that it may seal the fitting and engage the top of collar 40 to force the inside or high pressure pipe downwardly in the pile and seat the plug 21; a packing ring 46 being located between the top of collar 40 30 and bottom of gland 45 to seal the connection at that point.

As a convenient means for connecting a grab or tackle with the pile when the latter is to be handled, I provide the same with a 35 link 48 which is embedded in the pile adjacent the upper end thereof and preferably arranged vertically, so that the projecting ends 49 form horizontally opening apertures 50 through which a chain, or the like, (not 40 shown) may be extended to attach the pile to a suitable hoist.

It is apparent that with this construction, when the separate inner and outer conduits of the pile, represented by the sheet-iron 45 and tubing sections 4-5, and by the interior pipe 12, are connected with separate sources of water supply and the pile is lowered to the place where it is to be sunk, water discharged from the bottom of the pile 50 through the channel 19 will excavate in advance of the pile.

The water from the outer conduit, comprising the sheet metal and tubing sections, is delivered forcibly through the transverse tubes and upwardly from the flaring nozzles, so that the displaced material lifted from the excavation by the terminal nozzle is carried away by the upwardly directed jets of water delivered from the side nozzles 60 and stepped upwardly along the pile to the surface of the ground.

The terminal nozzle herein described is adapted for excavating in advance of the pile and the flared side nozzles are adapted 65 for delivering relatively wide, thin jets,

which feed films of water along the sides of the pile to lubricate the same, and being under pressure, have sufficient force to lift displaced material from one jet to another and step the same upwardly along the surface of 70 the pile, until it is delivered onto the surface of the ground through which the pile is sunk.

By forming the central portion of the core of the pile of relatively thin sheet 75 metal, the expense of the core is reduced, and by providing the sockets in the outer faces of the piling, the transverse tubes 32 may terminate within the surface of the pile and be provided with screw threads with 80 which the threads on the side nozzles may coöperate to removably mount the side nozzles on said tubes.

As the length of the pile is determined prior to its placement, the pipes may be 85 cut to proper length for arranging the nozzle flanges and connecting collars to properly seat the parts, and by providing the hoist links I adapt the structure for easy and quick connection with disconnection 90 from the hoisting device.

It is apparent that by connecting the upper fitting with the pile as described, the fitting and pipe 12 may be removed when a pile is sunk, so that it may be used repeatedly, and thereby effect a saving in the 95 equipment.

Having thus described my invention, what I claim as new therein, and desire to secure by Letters-Patent, is:

1. The combination with a body having a conduit extending therethrough, of a nozzle at the lower end of the body having a tapered channel, a pipe extending through the conduit and having a tapered head loosely 105 and removably seated in the tapered nozzle, and means at the upper end of the pipe for forcing said head to its seat and holding it there.

2. The combination with a body having a 110 conduit therein, of a nozzle at one end of the body provided with a tapered channel, a pipe removably located in said conduit, a hollow, tapered plug on said pipe adapted to seat against and seal the nozzle, and means 115 for forcing said plug to its seat and holding it there.

3. The combination with a body having a 120 conduit therein, of a nozzle in one end of the body having a tapered channel, a tapered plug seated in said nozzle and having an annular groove, a packing in said groove for sealing the nozzle channel, a pipe extending through the conduit and through the plug 125 and secured to the latter, and means for forcing the pipe toward the nozzle and holding it there.

4. The combination with a body having a 130 conduit therein, of a nozzle at one end of the body, lateral nozzles opening through the

body and communicating with the conduit, a pipe in said conduit, a channeled plug on said pipe seated in the nozzle, a collar on said pipe, a fitting inclosing a portion of the pipe and said collar, and a gland threaded into said fitting and bearing against the collar.

5. The combination with a body having a conduit therein, of excavating nozzle in one end of the body, lateral nozzles opening into the conduit and arranged around and turned upwardly along the sides of the body, a pipe in said conduit having a lower end seated in said nozzle, a fitting at the upper end of the body, a collar on said pipe within the fitting, a pipe section carried by said collar extending beyond the fitting, and a gland in said fitting inclosing the extension and bearing against the collar.
- 10 6. The combination with a concrete pile body having a longitudinal fluid conduit

therein and a link embedded in the body and having an annular portion surrounding said conduit and having end portions integral with the body and projecting from opposite sides of said body.

7. The combination with a concrete pile body having a longitudinal fluid conduit therein and a link embedded in the body and having end portions integral with the body 30 and projecting from opposite sides thereof and comprising horizontally opening eyes and having an annular portion surrounding said conduit and integral with said eye portions.

In testimony whereof I affix my signature in presence of two witnesses.

EDWARD BIGNELL.
